MANLY T. CARSON AND JAMES D. GURGANUS, OF WHISTLER, ALABAMA.

CAR-BRAKE.

SPECIFICATION forming part of Letters Patent No. 355,505, dated January 4, 1887.

Application filed October 26, 1886. Serial No. 217,230. (No model.)

To all whom it may concern:

Be it known that we, MANLY T. CARSON and JAMES D. GURGANUS, of Whistler, in the county of Mobile and State of Alabama, have 5 invented a new and Improved Car-Brake, of which the following is a full, clear, and exact description.

Our invention relates to car-brakes, and has for its object to provide simple, inexpensive, and readily-adjustable attachments to a car-body and brake-staff which will allow said staff and attachments to be lowered beneath the plane of the top of the car, to permit easy loading of lumber, car-wheels, railroad-iron, or 15 other heavy cumbersome freight on the car, and will allow the staff to be raised again quickly to operative position.

The invention consists in certain novel features of construction and combinations of parts 20 of the car-brake and its connections to the car-body, all as hereinafter fully described and claimed.

Reference is to be had to the accompanying drawings, forming a part of this specification, 25 in which similar letters of reference indicate corresponding parts in all the figures.

Figure 1 is an end view of part of the end of a platform-car with my improved brake connected thereto and the staff indicated in lowered position in dotted lines. Fig. 2 is a vertical sectional elevation of the foot of the erect car-brake staff and its connections with the car. Fig. 3 is a detail plan view with the brake staff in horizontal section; and Fig. 4 is a detail vertical sectional view of the brake-staff rest and adjacent part of the car.

The brake-staff A, at its lower end, is fitted to slide in projecting lugs b b of a cast-metal block, B, which is pivoted to turn transversely 40 of the car platform or body C on a cast-metal plate, D, which is fixed by bolts d d to the end sill of the car. The block B is connected to the plate D, preferably by the entrance of a boss, d', on said plate into a correspondingly-shaped 45 hole in the block, and outside of this boss there is placed on the bolt d, beneath its head, a washer, b', which overlaps the outer face of the block B and holds it quite snugly, but so as to turn freely on the boss d' as a center.

50 Directly under the lugs b b of the block B the main plate D is provided with upper and

lower lugs, d² d², in which is fitted loosely the revoluble socket E, which has a square or flat sided aperture, e, in its upper end, and into which the correspondingly-shaped lower end, 55 a, of the brake-staff A is adapted to fit, to cause the socket to turn as the brake-staff is turned. An eyebolt, F, passed through the socket E below the lower lug d² of the plate D, prevents lifting of the socket from its bearings and affords a means for attaching the brake chain to the socket, and whereby, when the socket is turned by the brake-staff, the chain (not shown) 60 may be wound onto the socket for applying the brakes to the wheels of the car, and may be unwound, for releasing the brakes, in a well-known manner.

In the brake-staff A, between the lugs b b of the block B, there is fixed a pin, G, which by contact with the upper lug, b, will prevent disconnection of the staff from the block when the end a of the staff is withdrawn from the brake chain socket E, as will be understood from Fig. 2 of the drawings, which also shows the socket E made hollow, which not only 75 relieves the socket of unnecessary weight and makes it stronger, but insures constant clearance of dust from its aperture e, to which the brake-staff is adapted, thus allowing the staff to be lowered fully when it is swung up 80 to the vertical position, at which time the block B will strike a lug or stop, H, on the main plate D, to hold the end a of the staff directly over the socket-aperture e and insure instant engagement of the staff and socket when the 85 staff is lowered, as shown in Fig. 1 of the drawings.

To the transverse car-sill or end beam there is fixed a bracket, I, having a half-round notch, i, into which the staff A falls or rests when the 90 staff is lowered, as shown in dotted lines in Figs. 1 and 3. I prefer to make the bracket I with a dowel, J, which enters a hole in the car-beam, thus allowing secure attachment of the bracket, so that it cannot swing out of proper 95 position, by a single bolt, K, passed through the bracket and car-beam. (See Fig. 4 of the drawings.)

To a lateral lug, b², on the pivoted block B there is pivoted a dog, L, which may be engaged with a ratchet-wheel, M, fixed to the 100 brake-staff A, to hold the brakes applied to

the car-wheels in the usual way, and the staff will be long enough to allow it to be operated conveniently from the car-platform by turning its hand-wheel A', which will stand at the side of the car when the brake-staff is lowered.

The operation of the brake is very simple and effective, as follows: We will suppose the brake-staff is in the vertical operative position shown in full lines in Fig. 1, with the staff A engaged with the brake-chain socket and drum E. Should it be desired to lower the staff, so as to leave the entire surface of the car-platform unobstructed all around, to allow lumber or machinery or car-wheels or railroad-iron to be loaded or unloaded conveniently, it is only necessary to lift the staff A a couple of inches, or until the pin G strikes the upper lug, b, of the block B. The staff then will be withdrawn from the brake-chain socket E, as in Fig. 2, and the staff then may be let fall or may be lowered into the notch i of the bracket I, and every part of the brake will be below the plane of the top of the car, as will be understood from the dotted lines in Fig. 1 of the drawings.

After loading the car, the brake-staff will be swung up again until the pivoted block B strikes the stop H, and the staff may then be lowered into the socket E, into operative position for applying or releasing the brake.

It will be noticed that there are no small parts of or attachments to the brake to get out of order or be lost, which is an important consideration in repairs as well as in first cost, and the brake-staff cannot be unshipped from the pivoted block nor the block from the main plate; hence the brake may always be operated with safety by the most inexperienced persons, and this last feature of the brake will be more apparent when it is considered that there are no bolts, pins, catches, or chained-up attachments to be unloosed or removed prior to operating the brake, which thus is as nearly automatic as it is possible for such contrivances to be made for practical use.

Having thus fully described our invention, what we claim as new, and desire to secure by Letters Patent, is—

1. In a car-brake, the combination, with a car body or platform, of a block, B, pivoted thereto, a staff, A, fitted for limited endwise movement and for rotation in the block B, and a socket, as E, carrying the brake-chain and held revolubly to the car-body, and to

which socket the end of the staff is adapted, substantially as described, for the purposes 55 set forth.

2. In a car-brake, the combination, with a car body or platform, of a block, B, pivoted thereto, a staff, A, fitted for limited endwise movement and for rotation in the block B, a 60 socket, as E, carrying the brake-chain and held revolubly to the car-body and to which the end of the staff is adapted for mutual movement, and a stop, as H, limiting the swinging movement of the staff when it is in position to 65 engage the socket, substantially as described, and for the purposes set forth.

3. In a car-brake, the combination, with a car body or platform, of a block, B, pivoted thereto, a staff, A, fitted for endwise movement and for rotation in the block B, a socket, as E, carrying the brake-chain and held revolubly to the car-body, and to which the end of the staff is adapted, and a rest, as I, fixed to the car-body to receive the lowered staff, substantially as described, for the purposes set forth.

4. In a car-brake, the combination, with a car body or platform, of a plate, D, fixed thereto and provided with lugs d² d² and a stop, H, a 80 block, B, pivoted to the plate D and provided with lugs b b, a brake-staff, A, fitted in lugs b and provided with a stop-pin, G, and a socket, E, fitted in the lugs d² of plate D and carrying the brake-chain and provided with 85 an aperture to receive the end of the brake-staff to be turned by it, substantially as described, for the purposes set forth.

5. In a car-brake, the combination, with a car body or platform, of a plate, D, fixed thereto 90 and provided with lugs d² and a stop, H, a block, B, pivoted to plate D and provided with lugs b b b², a brake-staff, A, fitted in lugs b b and provided with a stop, G, and a ratchet-wheel, M, a pawl, L, pivoted to lug b² of block 95 B and adapted to engage wheel M, and a socket, E, fitted revolubly in the lugs d² of plate D and carrying the brake-chain and provided with an aperture to receive the end of the brake-staff to be turned by it, substantially 100 as described, for the purposes set forth.
